United States Patent Office.

W. S. HILL, OF MANCHESTER, NEW HAMPSHIRE.

Letters Patent No. 95,228, dated September 28, 1869.

IMPROVEMENT IN WHIP-SOCKETS.

The Schedule referred to in these Letters Patent and making part of the same.

To all whom it may concern:

Be it known that J. W. S. HILL, of Manchester, in the county of Hillsborough, and State of New Hampshire, have invented a new and useful Improvement in Locking Whip-Socket; and I do hereby declare that the following is a full, clear, and exact description thereof, which will enable those skilled in the art to make and use the same, reference being had to the accompanying drawings, forming part of this specification.

The object of this invention is to combine, with a whip-socket for carriages, a lock with a swinging hasp, similar to a padlock, in such a way that the hasp may be locked around the whip, above the buttons or enlargements at the ends, when not using it, to prevent it from being wrongfully taken away, and so that when driving, and requiring it for use, the hasp being unlocked, may be opened, for readily inserting the whip in the socket, or removing it.

The invention also comprises an arrangement of leather, or other flexible substance, with the hasp and the lock, to prevent chafing the whip.

Figure 1 represents a sectional elevation of a socket and lock, arranged according to my improvement; and

Figure 2 represents a plan view of the same.

The socket A may be connected to the dash-board, or any other part of the carriage, in any approved way, so that room on the dash-board, or other part, may be had above the socket, on the attachment of the lock, which consists of a stock, B, provided with flanges, for attachment to the carriage, to which stock a hasp, C, is hinged at D, so as to swing therein, at the side opposite the joint.

The stock is provided with any suitable locking-device, enclosed in a case, E, into which the free end of the hasp projects when closed, and having any suitable key to work it.

Both the stock B and hasp C have semicircular recesses in the faces fronting each other, which, when closed, form a circular space or opening, coincident vertically with the socket for confining the whip.

These semicircular faces are grooved, and the grooves are filled with leather, India rubber, or other substance, as represented at F, which, when clamped around the whip, will not chafe or injure it.

These locks are specially adapted for use with the whip-sockets; and constitute, when attached together, a very convenient and secure attachment for holding and securing the whip.

When driving, and requiring the whip for use, the hasp may be kept unlocked.

Having thus described my invention,

What I claim as new, and desire to secure by Letters Patent, is—

1. The combination, in a whip-socket, of a clasp-lock B C E, when arranged for application to the dasher or other part of the carriage, in connection with the socket, substantially as specified.

2. The combination, with the parts B C, grooved, as described, of leather or other similar guards, F, for the protection of the whip, substantially as specified.

W. S. HILL.
